UNITED STATES PATENT OFFICE.

DANIEL S. WAUGH, OF DENVER, COLORADO, ASSIGNOR, BY MESNE ASSIGNMENTS, TO THE DENVER ROCK DRILL MANUFACTURING COMPANY, OF DENVER, COLORADO, A CORPORATION OF DELAWARE.

ROCK-DRILL.

1,178,892.

Specification of Letters Patent. Patented Apr. 11, 1916.

Application filed April 17, 1912. Serial No. 691,371.

To all whom it may concern:

Be it known that I, DANIEL S. WAUGH, a citizen of the United States, residing at Denver, in the county of Denver and State 5 of Colorado, have invented new and useful Improvements in Rock-Drills, of which the following is a specification.

The present invention relates to rock drills, and more particularly to the means 10 for introducing a cleansing fluid into the drill hole, to remove the cuttings therefrom.

The primary object is to provide a simple and effective structure for this purpose that will be economical in use, at the same time 15 having a high degree of efficiency, and furthermore it is so constructed that the parts thereof, are not liable to be excessively worn, injured, or cut in use.

The preferred embodiment of the invention 20 is illustrated in the accompanying drawings, wherein:—

Figure 1 is a side elevation, partly in section of a hammer drill, embodying the invention. Fig. 2 is a section on an enlarged 25 scale of a portion of the same. Fig. 3 is a section still further enlarged of the valve mechanism, and illustrating more clearly the passages by which the cleansing fluid is conducted to the internal tube. Fig. 4 is a sectional view on the line 4—4 of Fig. 2. Fig. 5 is a detail sectional view on the line 5—5 of Fig. 4. Figs. 6, 7 and 8 are respectively, sections taken on the lines 6—6, 7—7, and 30 8—8 of Fig. 2. Fig. 9 is a sectional view 35 taken on the line 9—9 of Fig. 1. Figs. 10 and 11 are respectively, detail sectional views taken on the lines 10—10 and 11—11 of Fig. 1. Fig. 12 is a sectional view taken 40 on the line 12—12 of Fig. 3. Fig. 13 is a longitudinal sectional view taken on the line 12—12 of Fig. 3 showing a detail of the coupling member.

Similar reference numerals designate corresponding parts in all the figures of the 45 drawings.

In the embodiment illustrated, the drill comprises a cylinder member 13, having at one end a chuck 14, and at its other end, a head block 15. Within the cylinder member 50 operates the usual reciprocating piston 16, which strikes against a tappet 17 interposed between said piston and the inner end of the usual removable drill bit or steel 18. Secured to the head block 15, is the cylinder 55 19 of the usual fluid-operated feeding

means, a piston 20, operating in said cylinder and having a piston rod or stem 21 that projects from its rear end and is pointed to produce a spur 22. In the present embodiment, the cylinder 19 is secured in place on the head block by a split clamping band 23, the ends of which are drawn together by a bolt 24, and the parts being held against relative movement by a plug 25 threaded through the band 23 and extending transversely 60 through the end of the cylinder 19 and the portion of the head block surrounded by said cylinder, as illustrated in Fig. 2.

Interposed between the head block and the rear end of the cylinder 13, is a support 70 in the form of a closure plate 26, having a central opening 27 therethrough, communicating with a socket 28. A cleansing fluid-conducting tube 29 extends axially through the cylinder member 13, and into the opening 27 of this closure plate. The rear end of this tube is flanged, as illustrated at 30, the said flange being located in the socket 28, and a plug 31, threaded into the socket, bears against the flange to maintain the tube 80 in place. This tube, it will be observed, extends through a bore 32 in the piston, and its front end is located in the tappet 17, said tappet being provided with a bore 33 snugly receiving said end. The tappet in advance 85 of the tube 29, has a reduced passageway 35 that is in alignment and communicates with the rear end of a passageway 36 formed longitudinally in the drill bit or steel 18.

Motive fluid is supplied to the machine 90 through a tube 37, connected by a coupling 38 that is threaded into one side of the head block 15, said coupling having an internal chamber 39. An initial or controlling valve 40 is rotatably mounted in the head block, in line with the said coupling 38, being provided with a handle 41 projecting from the side of the head block opposite to the said coupling 38. The valve has its end recessed, as illustrated at 42, and leading therefrom, is a supply port 43 movable into and out of communication with a port 44 formed in the head block, said port 44 opening into a chamber 45 formed between the closure plate 26 and the head block. From the chamber 45, a passage 46 leads to the valve casing 47, in which is located an automatic valve 48 that controls the supply of motive fluid to the cylinder member, on opposite sides of the piston 16, for the purpose 105 110

of reciprocating said piston. Inasmuch as the particular structure of this valve constitutes no part of the present invention, it is believed to be needless to describe the same, and it will be evident that valves of various characters may be employed. It may be noted, however, that the valve casing constitutes the means for connecting the handle 49 to the cylinder member 13, for the purpose of rotating or oscillating the drill.

A socket 50 is formed in the end of the coupling 38, and a reduced port 51 leads from the chamber 39 into this socket. Extending from one side of the said socket 50, and illustrated more particularly in Fig. 12, is a passage 52 leading to an annular channel 53 formed between the coupling 38 and the head block (see Fig. 3), and from this channel 53, extends an angular passage 54 that opens into an annular chamber 55 surrounding the flange 30 of the tube 29, and the inner end of the plug 31. Ports 56 in said plug lead from the chamber 55 to the hollow interior 57 of the plug, and thus afford communication with the bore of the tube 29.

The passage of the gaseous motive fluid from the chamber 39 to the tube 29, by way of the above described conduit, is controlled by a plug valve 58 that moves into and out of the port 51 to close the same. This plug valve is provided with a stem 59, having a screw threaded engagement with a cuff 60 that is pinned, as shown at 61, to a rotatable actuating handle 62 rotatably mounted on the projecting end of the coupling 38, and held in different positions by a spring-pressed plunger 63. The cuff 60 is journaled in a sleeve 64 that is threaded into the socket 50 of the coupling, and this sleeve is provided with diametrically opposite slots 65, in which are engaged the ends of a cross pin 66 carried by the stem 59 of the plug valve 58. With this arrangement, it will be evident that if the head or handle 62 is rotated, the cuff 60 will be correspondingly turned, and inasmuch as the valve 58 cannot turn with it, the threads will carry the said valve into or out of the port 51, thus closing or opening said port, and permitting the gaseous fluid, under pressure, to flow from the chamber 39, through the port 51, the socket 50, the passageway 52, channel 53, passageway 54, chamber 55, and ports 56 into the interior 57 of the plug, and from thence into and through the tube 29. Passing from the front end of this tube 59, the said fluid will enter the port 35 in the tappet, and consequently be delivered into the passageway 36 of the drill bit.

Means is also provided for introducing a cleansing liquid into the drill hole, and this liquid is supplied from any suitable source, through a tube 67, having a controlling valve 68 therein. The tube 67 has an elbow

connection 69 with the coupling 38, and the passageway therethrough communicates with the passageway 52, so that, by turning the valve 68 to open position, the liquid will enter the passageway 52, and pass, by the above described course, to the drill bit.

The initial valve 40, as shown more particularly in Fig. 4, is provided with a transverse port 70 that moves into and out of communication with a passage 71 leading to the air feed cylinder 19, and when the said valve is turned toward its open position, the port 70 is first brought into communication with the passage 71, to cause the fluid, under pressure, to enter the cylinder 19 and move the machine to its work. Upon a further movement of the valve, the port 43 is brought into communication with the port 44, and the motor is thus thrown into operation, as already described. When this movement takes place, as illustrated in Fig. 4, the port 70 moves out of communication with the port 71, and another port 72 is brought into communication with a passageway 73, leading to the front end of the cylinder member, where it communicates with a transverse port 74 normally closed by the tappet 17. Diametrically opposite the port 74 is another transverse port 75, communicating with a passageway 76 that leads rearwardly and is brought into communication with the passage 71, by means of a channel 77 formed in one side of the initial valve 40. The operation of this arrangement is such that when the tappet 17 is moved forwardly sufficiently, the ports 74 and 75 will be brought into communication, and the pressure in the feed cylinder 19 will be varied. This feature in itself constitutes the subject-matter of Patent, No. 969,319, granted September 6, 1910, and needs no further illustration. Attention is called, however, to the fact that leading from the passageway 73, is a port slot 78 communicating with a passageway 79 that leads to an annular channel 80, formed in the chuck. From this channel 80, rearwardly and inwardly inclined ports 81, shown more particularly in Fig. 2, lead to another internal channel 82, surrounding the socket for the drill bit, the inner open side of this channel 82 being normally closed, or substantially closed by the bit when in place.

Briefly described, the operation of the apparatus is as follows: Upon turning the initial or throttle valve 40 from its closed position, the first action is to deliver the fluid, under pressure, to the feed cylinder, which will cause the motor and drill to be carried to its work. A further movement of the valve supplies the motor with actuating fluid, causing the hammer piston 16 to deliver its blows to the tappet 17, and said tappet transmits the force of these blows to the drill steel introduced into the chuck.

When it is desired to moisten the cuttings in the drill hole, it is only necessary to open the valve 68, whereupon the liquid will flow into the tube 29, and passing through the 5 tappet, will enter the drill bit. If it is desired to blow out the cuttings by the air or gaseous fluid under pressure, the plug valve 58 is opened, whereupon the said gaseous fluid will pass through the drill bit to the 10 bottom of the drill hole. If desired, both liquid and gaseous fluids may be delivered by opening or partially opening both valves simultaneously. It will of course be understood that there will be some leakage of the 15 liquid between the drill bit and the end of the tappet, but by providing the channel 82 around the drill bit, and supplying this channel with fluid under pressure, a substantial seal is provided that will prevent to 20 a very great extent, leakage around the drill steel, and furthermore this fluid has a tendency to move inwardly. In fact, part of such fluid will thus escape, so that it will find its way into the passage of the drill bit. 25 It is also to be noted that the tappet in this structure performs three distinct functions. It operates to transmit the blow of the piston to the drill bit. It prevents leakage of the 30 actuating fluid from the piston to the drill bit, and it constitutes part of the means for delivering cleansing fluid to the drill bit. Furthermore by inclosing the end of the cleansing fluid conducting tube, it protects the same against being battered, cut or otherwise injured.

From the foregoing, it is thought that the construction, operation and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. In a drilling machine, the combination 50 with a fluid actuated motor and a drill bit associated therewith, the latter having a passageway therein, of means for delivering cleansing fluid through the motor to the drill bit, means for preventing the passage 55 of the actuating fluid from the motor to the drill bit, and means other than the first delivering means having communication with the drill bit for supplying other cleansing fluid to the same in advance of said preventing means.

2. In a drilling machine, the combination 60 with a fluid actuated motor including a cylinder member and a reciprocating piston operating therein, of a drill bit associated with the motor and having a passageway

therein, means for delivering one kind of cleansing fluid through the piston to the drill bit, means other than the first delivering means for delivering another kind of cleansing fluid to the drill bit, and means 70 for preventing the passage of the actuating fluid from the motor to the drill bit.

3. In a drilling machine, the combination 75 with a fluid actuated motor including a piston and a drill bit associated therewith, the latter having a passageway therein, of cleansing fluid supply means associated with the motor and extending through the piston, and means for preventing the passage of the actuating fluid from the motor to the 80 drill bit, said latter means also constituting means for directing the cleansing fluid from the supply means to the drill bit.

4. In a drilling machine, the combination 85 with a fluid actuated motor including a cylinder member and a reciprocating piston operating therein, of a tube for cleansing fluid extending through the piston, and a tappet interposed between the piston and drill bit for transmitting the flow of the former to the latter and having a front abutment shoulder for the rear end of the drill bit, said tappet constituting means for preventing the passage of the actuating fluid from the motor to the drill bit, and having a port that constitutes means for directing the cleansing fluid from the front end of the tube to the rear end of the drill bit.

5. In a drilling machine, the combination 100 with a fluid actuated motor including a piston, of a drill bit having a passageway, a tappet interposed between the piston and drill bit and having a front abutment face for the rear end of the bit, and a cleansing 105 fluid conducting tube extending into the tappet and terminating therein short of the abutment face, said tappet having a bore that affords communication between the front end of the tube and the rear end of the 110 bit, for conveying cleansing fluid from the tube to the bit.

6. In a drilling machine, the combination 115 with a fluid actuated motor including a reciprocating piston having an axial bore, of a drill bit in line with the piston and having an axial passageway, a tappet interposed between the piston and drill bit and being also provided with an axial bore, and a cleansing fluid conducting tube extending 120 longitudinally through the piston and snugly fitting in the bore of the tappet, the front end of said tube terminating in the tappet bore short of the front end thereof, said bore thereby constituting means for conducting fluid from the tube to the drill bit.

7. In a drilling machine, the combination 125 with a motor having a chuck, of a drill bit removably fitted in the chuck, means for de-

- livering cleansing liquid through the inner end of the drill bit, and means for producing a gaseous fluid seal in the chuck around the bit.
8. In a drilling machine, the combination with a motor having a chuck, of a drill bit removably fitted in the chuck, means for delivering cleansing liquid into the bit, said chuck having a fluid channel surrounding the drill bit, and means for delivering gaseous fluid under pressure into the channel.
9. In a drilling machine, the combination with a motor including a piston, of a drill bit having a passage therethrough, means for delivering cleansing liquid through the piston to the drill bit, and means for producing a fluid seal around the drill bit to prevent leakage of the cleansing liquid past the same.
10. In a drilling machine, the combination with a motor, including a cylinder member, of a reciprocating piston operating therein, a chuck carried by the cylinder member and having a drill bit receiving socket and a fluid channel surrounding and communicating with the socket, means for delivering cleansing fluid to the inner end of the drill bit, and means for introducing gaseous fluid under pressure to the channel, to provide a seal about the drill bit.
11. In a drilling machine, the combination with a fluid actuated motor, including a cylinder member, of a reciprocating piston operating therein, a chuck secured to the cylinder member and having an internal fluid channel, a drill bit detachably located in the chuck and having a passageway therethrough, a tappet interposed between the drill bit and piston, a cleansing fluid conducting tube extending through the piston and terminating in the tappet, means for introducing a cleansing fluid into said tube, and means for introducing a gaseous fluid under pressure to the internal channel of the chuck.
12. In a drilling machine, the combination with a cylinder member, of a piston operating therein, a closure plate for the cylinder member having a rearwardly opening socket, a tube extending through the piston member and having a flanged end located in the socket of the closure plate, a plug threaded into the socket and bearing against the flange, and means for introducing fluid into the tube and including lateral ports opening through said plug.
13. In a drilling machine, the combination with a cylinder member, of a head block secured to the rear end thereof, a closure interposed between the head block and cylinder member and held in place thereby, said closure having a central socket, a reciprocating piston operating in the cylinder member, a tappet engaged by the piston, a tube having a flanged end in the socket of the closure and having its other end in the tappet, means for securing the said end in the socket, and means for introducing motive fluid into the tube.
14. In a drilling machine, the combination with a cylinder member, of a head block secured to the rear end thereof, a tube projecting into the cylinder member, means for connecting a fluid supply to the head block, including a coupling projecting from one side of said block, a passage extending from the coupling to the tube, and a controlling valve for the passage mounted on the free end of the coupling and disposed longitudinally thereof.
15. In a drilling machine, the combination with a cylinder member, of a head block secured to the rear end thereof, a tube projecting into the cylinder member, means for connecting a gaseous fluid supply to the head block, including a coupling projecting from one side of said head block, a passage extending from the coupling to the tube, a fluid supply communicating with the passage, and a valve in the passage controlling the supply of gaseous fluid to the tube.
16. In a drilling machine, the combination with a cylinder member, of a head block secured to the rear end thereof, a closure plate interposed between the head block and cylinder member, a tube mounted on the closure plate and projecting axially through the cylinder member, means for separately supplying a liquid and a gaseous cleansing fluid to the tube, including a coupling projecting from one side of the head block, a valve mounted on the end of the coupling for controlling the passage of one of the fluids to the tube, a reciprocating piston operating in the cylinder member and having an axial bore that receives the tube, a chuck carried by the end of the cylinder member and having an internal channel surrounding the bit socket, a bit detachably located in the socket and having a passage therethrough, a tappet interposed between the drill bit and piston and having a bore that communicates with the passage of the bit and snugly receives the end of the tube, and means for introducing a gaseous fluid into the channel of the chuck and around the drill bit.
17. In a drilling machine, the combination with a fluid-actuated motor, including a cylinder member and a piston operating therein, of a drill bit actuated by the piston and associated with the motor, said bit having a passageway therethrough, means for delivering a cleansing fluid through the piston to the drill bit, and means for preventing the escape of said cleansing fluid around the drill bit, said latter means also supplying a cleansing fluid to the drill bit.
18. In a drilling machine, the combination with a fluid-actuated motor, including a cylinder member and a piston operating

- therein, of a drill bit actuated by the piston and associated with the motor, said drill bit having a passageway therethrough, means for delivering a cleansing liquid through the 5 piston to the drill bit, and means for preventing the escape of said cleansing liquid around the drill bit, said means also supplying a gaseous cleansing fluid to the drill bit.
19. In a drilling machine, the combination 10 with a fluid-actuating motor, including a cylinder member and a piston operating therein, of a drill bit actuated by the piston and associated with the motor and having a passageway therethrough, a tube extending 15 through the piston and delivering a cleansing liquid to the drill bit, means inter-
- posed between the drill bit and piston for producing a fluid-tight joint therebetween, and means for forming a gaseous seal around the inner end of the drill bit, said means 20 having communication with the inner end of the drill bit, to permit the passage of fluid from said seal to the passageway in the drill bit.
- In testimony whereof I have hereunto set 25 my hand in presence of two subscribing witnesses.

DANIEL S. WAUGH.
